UNITED STATES PATENT OFFICE.

GEOERGE BYRON CARROLL, OF EAST LANSING, MICHIGAN.

COMBINATION WHEELBARROW.

Application filed June 19, 1922. Serial No. 569,392.

To all whom it may concern:

Be it known that I, GEORGE B. CARROLL, a citizen of the United States, residing at East Lansing, in the county of Ingham and State of Michigan, has invented certain new and useful Improvements in a Combination Wheelbarrow; and I do declare the following to be a full, clear, and exact description of the invention, such as will enable others skilled in the art to which it appertains to make and use the same.

This invention relates to an improved article carrier which is capable of being converted to provide an ordinary wheel barrow or a carrier for milk cans and the like.

The principal object of the invention is to provide a carrier of this class which embodies a wheel-supported frame on which the box or article container of the barrow is mounted, this box having its bottom connected with the frame in a manner to permit it to be suspended beneath said frame when the latter is swung over to invert it, whereby to provide a platform on which milk cans or other articles may be supported.

Another object of the invention is to provide a carrier of the above construction, wherein the preferred means for connecting the platform with the frame is such as to permit the platform to be raised or lowered to the different elevations independent of the frame.

A still further object of the invention is to provide novel means between the suspension devices and the frame for limiting the swinging movement of the platform in a rearward direction when the device is used as a carrier for milk cans.

Other objects and advantages of the invention will be apparent during the course of the following description.

In the accompanying drawings forming a part of this specification and in which like numerals are employed to designate like parts throughout the same:

Figure 1 is a side elevational view of a carrier constructed in accordance with this invention showing the same arranged for carrying milk cans.

Figure 2 is a central longitudinal section of Figure 1 showing the frame raised off of the floor, ground, or other place on which the carrier is rested.

Figure 3 is an elevational view showing the parts reversed to provide a wheel-barrow.

Figure 4 is a top plan view of Figure 1 with the cans removed.

Figure 5 is an enlarged view showing one of the details of the invention.

In the drawings, the numerals 1 designate the spaced parallel side-bars of a supporting frame which are connected at their forward ends to a single wheel 2. To each of these side-bars adjacent the inner ends, legs 3 are connected. It is to be noted that these legs are connected to the side-bars intermediate their ends so that they project on both sides of the bars and serve as supports for the frame in either of its positions.

As before intimated, the improved carrier is capable of use in the capacity of a wheelbarrow when arranged in one manner, and is capable of being converted to provide a novel carrier for milk cans or the like when arranged in another manner. For the sake of convenience of description, attention will first be confined to the use of the device as a carrier for the milk cans C. Reference being had more particularly to Figures 1, 2 and 4, it will be seen that the numeral 4 designates a platform which is suspended in spaced relation below the side-bars of the aforesaid frame by a plurality of pairs of links 5, the upper links of each pair converging and being pivotally connected to the intermediate portion of the side-bars 1 as indicated at 6 while the lower links 7 are pivotally connected with the lower ends of the upper links and diverge and are pivotally connected at their lower ends to the platform 4 adjacent the corners thereof as indicated at 8. It may be conveniently stated here that the links of each pair are adjustably connected together through the medium of removable pins 9 which are selectively passed through the aligned holes of a series of holes formed in the overlapping ends of the links. It is obvious that this particular connection for the links of each pair is provided to permit the elevation of the platform to be varied independent of the frame for supporting smaller cans or articles.

Although I have shown and described a particular method of enabling the platform to be vertically adjusted with respect to the supporting frame, I wish it to be understood that any other suitable means may be provided for accomplishing this end.

As before indicated, novel means is provided between the links and frame to limit

the swinging movement of the platform in one direction. Although this means could be of some other construction, it preferably comprises a pair of disks 9' which surround the pivot pins 6 and are arranged between the links and side-bars of the supporting frame. Each disk is provided on its inner face with a raised portion 10 providing a shoulder. This projection 10 is substantially 5 triangular and the upper links of the right-hand pairs of links abut against one inclined edge as shown clearly in Figure 5. Since the links of each pair are connected together by the hereinbefore described means and held 10 against relative pivotal movement, it will be seen that the movement of the platform can be limited in this manner. It is to be noted that the disks 9' are rotatable on the pivot pins 6 so as to permit folding of the links to 15 permit them to assume the positions disclosed in Figure 3. However, means is provided for maintaining these disks against rotation when the device appears as shown in Figure 1. Although this means could be 20 of some other construction, it simply comprises pins 11 passing through holes in the disks and side-bars 1. It is obvious that by removing the pins 11, the disks will be free 25 to rotate and permit the aforesaid folding 30 of the links.

From the foregoing description it is obvious that I have devised a carrier embodying a wheel supported frame from which is suspended, through the medium of pairs of 35 diverged links, a platform on which milk cans or the like are designed to be supported. The platform is adjustable toward and from the supporting frame and is substantially "self-leveling." However, the swinging 40 movement is limited one direction by novel means herein described.

When it is desired to convert the device from a milk can carrier to a wheel barrow, it is only necessary to grasp the side-bars 45 and swing them over to the left to bring the legs 3 which are then extending above the bars to a position to engage the floor on the other side of the wheel. In so doing the aforesaid platform 4 drops down onto the upper edges of the side-bars and provides a bottom for the box of the barrow. It is of course necessary to remove the connecting pins 9 before the links of the pairs 50 are permitted to fold to assume the relations shown in Figure 3. It is also necessary to remove the locking pin 11 to permit rotation of the aforesaid disks 9'. Attention being now directed to Figure 3, it will be seen that the aforesaid platform, is provided with openings 12 to receive the lower extended ends of brackets 13 carried by the side-boards 14 of the barrow box. These side-boards at their forward ends, are received in vertical grooves 15 formed in the end-board 16. Although it is not essential,

it is desirable to permanently secure the end-board 16 to the side-bars 1 so that it will at all times be in position for ready use.

A careful consideration of the foregoing description taken in connection with the drawings will doubtless be sufficient to enable persons skilled in this art to obtain a clear understanding of the invention, the several features and advantages thereof, and the manner of forming both the barrow 75 and carrier for milk cans and the like. Therefore, a more lengthy description is thought unnecessary.

Since probably the best results may be obtained with the construction and arrangement herein shown and described, this is taken as the preferred embodiment of the invention. However, I wish it to be understood that minor changes coming within the scope of the invention as claimed 85 may be resorted to if desired.

I claim:

1. A convertible carrier comprising a wheel supported invertible frame, a body supported on the upper side thereof and 90 including a vertically disposed end-board and a bottom having one end abutting said board, links pivotally connected with said bottom and with the side bars of said frame to permit the bottom to be suspended in 95 horizontal spaced relation below said board when the frame is inverted.

2. A convertible carrier comprising a wheel-supported invertible frame, a body supported on the upper side thereof and 100 including a vertically disposed end-board and a bottom having one end abutting said board, said bottom being provided with means to permit connection of side-boards thereto, links pivotally connected with said bottom and with the side-bars of said frame 105 to suspend the bottom in a horizontal spaced position below said board when the frame is inverted.

3. An article carrier comprising a wheel 110 supported frame, a platform spaced beneath the latter, pairs of divergent links pivotally connected with the frame and platform, the inner ends of said links being pivotally connected in overlapping relation 115 and provided with vertically spaced aligned holes to receive removable pins for preventing relative movement of the links of each pair.

4. A convertible carrier comprising a pair 120 of spaced side-bars, a wheel to which the outer ends of said bars are connected, supporting legs secured intermediate their ends to the intermediate portions of said side-bars, said legs being disposed vertically and 125 extending on opposite sides of said side-bars to support the latter in an elevated position when in either position, a board secured to said side-bars adjacent their points of connection of said wheels, said 130

board depending below said bars, a platform arranged in horizontal spaced relation beneath said side-bars, and suspension means pivotally connected with said platform and side-bars to permit the platform to be rested against the side-bars to provide the bottom of a barrow box when the side-bars are swung over to invert them in the manner described.

10 5. A convertible article carrier comprising an invertible frame, a platform spaced

therefrom, pairs of divergent links pivotally connected with the frame and platform, and a stop associated with the pivotal connection of the links with the frame, said 15 stop being normally stationary, but capable of rotation to permit the degree of divergence of the links to be varied when the parts are inverted.

In testimony whereof I have hereunto 20 set my hand.

GEORGE BYRON CARROLL.
